CUSHION LUG STRAP

J. Edgar Moe, Danielson, Conn., assignor to The Bullard Clark Company, Danielson, Conn., a corporation of Connecticut

Application February 15, 1949, Serial No. 76,600

2 Claims. (Cl. 139—153)

1

My present invention is a novel and improved lug strap for use in actuating the picker stick in a loom, and the object of the invention is to improve and perfect devices of this type.

It is well known that such lug straps are subjected to extreme wear and violent strains necessarily due to the service involved in actuating the picker stick to throw a shuttle widthwise of the loom and to receive the return action of the shuttle. For many types of looms, such lug straps are generally of U-shaped formation, with the forward arms of the U being adapted to be bolted to a sweepstick, the other movable part which is actuated to force the picker stick to throw the shuttle by a violent and quick jerking action, whereby the strains are transmitted thru the lug strap from the bolts holding the same at one end, and the heel of the lug strap which contacts the picker stick at the opposite or U-shaped part of the lug strap.

It has been found important and desirable to provide a construction wherein a slight yielding action will cushion or soften the blow of the picker stick to the lug strap, as well also as to cushion the return action of the picker stick as it receives the shuttle from across the loom when thrown from the opposite side.

Too great rigidity in the lug strap, therefore, is liable to break or unduly wear the picker stick or lug strap itself; whereas too much resiliency in the construction of the lug strap will waste power, render the shuttle action uneven and uncertain, and cause objectionable results in the cloth being woven.

In my prior Patent No. 2,445,744, issued July 20, 1948, I illustrated a lug strap construction wherein considerable yield was provided in a lug strap between the bolt slots and heel of the strap.

In my present invention I have devised a novel form of construction wherein sufficient yielding or resilient action is provided to cushion the blows of the picker stick both in the throwing and receiving actions wherein a relatively rigid structure extends thru the arms and around the heel of a bolt strap on the outside, together with a cushioning structure on the inside of the U-shaped arms and heel, in combination also with relatively inflexible wear-resisting layers on the inner face of the lug strap to take up the wear and lateral strains involved by contact with the picker stick.

My invention provides a plurality of layers, one being a cushioning element which is supported and protected within the confines of the outer layer of the lug strap arms and heel por-

tion, together with a wear-resisting and relatively inflexible inner layer or part against which the picker stick will bear and slide. Thus, the cushion element is held and protected between an interior relatively rigid layer and an outer relatively rigid layer. However, in order to afford full yielding capacity to the inner yielding element, I separate or divide the inner layer or layers at any predetermined position desired so as to give full capacity to the yielding element at the heel portion of the lug strap, as will be more fully explained.

I may utilize any desired material for the inner and outer inflexible, and relatively rigid layers, such for example as metal, wood, hard synthetic plastic material, or the like. For the inner yielding material, I may utilize rubber, rubberlike compounds, a yielding synthetic plastic or the like resilient means preferably in combination with a heel plug which may be of interwoven canvas, relatively hard rubber, or the like.

In carrying out my invention, I find that a suitable material for the outer and inner relatively inflexible layers is plywood, which can enclose the rubberlike cushioning elements therebetween and be readily bent into desired U-shaped conformation to form the lug strap, which encloses a heel plug against which the picker stick strikes. With the inner plywood layer separated or cut at a suitable point between the bolt slots at the open end of the U-shaped arms of the lug and the face of the heel plug, I thus obtain a structure which gives full capacity for the cushioning action of the inner layer, which is backed up by the solid outer layer around the heel strap and also gives ample strength for wear-resistance against the sides of the picker stick as it travels between the bolt slots and the face of the heel plug.

Referring to the drawings illustrating a preferred embodiment of the present invention:

The figure shows a typical type of U-shaped lug strap having side arms designated generally at 1 and 2, and a heel portion 3. These side arms comprise an outer layer 4 of suitable length and width for the loom to which they are to be attached, and may be of a plurality of layers of plywood or any other relatively inflexible material as above explained. At the open end portions adjacent the bolt slots 5 and 6, I provide additional plywood or relatively inflexible material 7 and 8 to which the inner layers 10 and 12, respectively, in each arm are united by adhesive; and in the case of plywood a resinous material is employed the same as that employed uniting

the layers of plywood. Thus, a firm, rigid structure for the lug strap is built at the forward or open end of the arms thru which the bolt slots 5 and 6 are cut and in which the bolts are secured to the sweepstick or other power-actuating link of the loom.

An inner resilient layer 15 extends around the heel portion 3 of substantially the same thickness as that of the intermediate layers 7 and 8 constituting a cushion around the heel portion 3 and being bonded to the inner surface of the outer layer 4. This resilient layer 15 extends throughout the entire width of the outer layer 4 as well as that of the inner forward layers 10 and 12, so far as they overlap, as shown in the drawing.

In order to give proper and full capacity for the actuation of the resilient layer 15 during contacts of the picker stick against the heel plug 20 and yet also to continue the proper thickness of the walls of the arms 1 and 2 and the wear-resisting surface of the lug strap against the picker stick, I provide a separate inner lining, layer, or element 21 extending around the heel plug 20 and a substantial distance along the inside of the resilient layer 15 adjacent the heel plug. This U-shaped part 21 corresponds in thickness and strength to the inner layers 10 and 12 but is divided therefrom to permit the action of the resilient layer 15 to be effective.

Preferably I form the inner ends of the layers 10 and 12 and the heel end layer 15 along a slanting line spaced from each other as indicated at 22 and 23, such slanting lines, as shown at 25, extending throughout the width of the heel strap, arms, and in opposite directions to provide an overlapping so that the picker stick as it reciprocates between the slots and heel plug will at all times have a proper widthwise bearing on the inner layers 10 and 12 and the arms of the heel layer 21.

Thus it will be appreciated that I have devised a novel and effective cushioning lug strap with a relatively rigid structure at the bolt slots and around the outside of the heel plug, with the intermediate resilient layer of substantial extent to encircle the heel plug, in combination with the inner protecting wear-resisting layer for contact with the picker stick itself.

My lug strap is so constructed that it divides the inner wear-resisting layer as to permit full

yielding capacity of the resilient layer 15 where the plug 20 compresses same during use and also to give continuous wear-resisting contact between the inside of the arms of the lug strap and the picker stick being actuated therebetween.

I claim:

1. A lug strap of the kind described, comprising a heel plug and U-shaped arms formed of a plurality of widthwise layers, the outermost layer being of relatively inflexible material and extending continuously lengthwise of the arms and the heel of the U-shaped portion, the inner layer being of relatively inflexible material and consisting of three portions, said layers enclosing a relatively resilient layer extending around the heel and along the side arms, together with a heel plug fitted within the innermost layer extending around the heel portion, the two innermost portions being spaced along slanting lines between the heel plug and the ends of the open arms.
2. A lug strap of the kind described, comprising a heel plug and U-shaped arms formed of a plurality of widthwise layers, the outermost layer being of relatively inflexible material and extending continuously lengthwise of the arms and the heel of the U-shaped portion, an inner layer of relatively inflexible material adjacent the open ends thru which bolt slots are formed, a second inner layer of inflexible material extending around the heel portion and in which the heel plug is enclosed, and an intermediate layer of relatively resilient material extending entirely around the heel portion between the outermost layer and the adjacent innermost layer, said resilient layer constituting a portion of the arms adjacent the bolt slot and all of said layers being united by bonding material, and the adjacent ends of the innermost inflexible layers being spaced widthwise of the arms, said spaced ends being spanned by the relatively resilient layer.
